D. C. McCRAY

IRONING CABINET

Filed Oct. 31, 1924

UNITED STATES PATENT OFFICE.

DAY CHANNING MCGRAY, OF OSHKOSH, WISCONSIN, ASSIGNOR TO NATHAN PAINE, OF MIAMI BEACH, FLORIDA.

IRONING CABINET.

Application filed October 31, 1924. Serial No. 747,023.

The invention relates to ironing cabinets and more particularly to the type which is adapted to be built into the wall of a room.

The object of the invention is to provide an ironing cabinet of simple and durable construction whereby one or more ironing boards may be compactly housed and readily brought to a rigid operative position, and more specifically the object is to improve on the construction of the device disclosed in my copending application Serial No. 670,894, with the view of facilitating assembly and effecting economies in manufacture.

The invention further consists in the several features hereinafter set forth and more particularly defined by the annexed claims.

In the drawings, Fig. 1 is a front elevation of the device before being installed and with the parts in their closed position, parts being broken away and parts being shown in section;

Fig. 2 is a vertical sectional view taken on the line 2—2 of Fig. 1;

Fig. 3 is a view similar to Fig. 2, but with the parts in their open position;

Fig. 4 is a fragmentary detail view of one side of the housing frame, parts being shown in section;

Fig. 5 is a transverse sectional view taken on the line 5—5 of Fig. 1 with the ironing board removed but including a door and casing; and

Fig. 6 is a detail perspective view of one of the ironing board supports.

In these drawings numeral 10 designates a vertically disposed rectangular housing frame closed at the rear by a panel 11, preferably of veneer. The frame 10 includes uprights 12 rigidly secured in spaced relation by cross members 13 and the panel 11. The frame is adapted to be built into the wall and for this purpose is provided with a casing 14 on which is hinged a door 15, as seen in Fig. 5.

The ironing board 16 of usual shape has one end formed with a groove 17 in which is saddled a cylindrical rod 18 secured to the board to form trunnions 19 projecting beyond the edges of the board a distance suitable to pass between the uprights 12 of the frame 10. The trunnions 19 are adapted to move along the edges of aligned L-shaped guides 20 nailed or otherwise suitably secured to the inner faces of the uprights 12,

the lower legs 21 of the guides projecting forwardly adjacent the intermediate cross member 13 of the housing frame.

In the closed position of the device, as seen in Fig. 2, the trunnions 19 rest on the upper edges of the legs 21, and the board is retained in a vertical position by its disposition behind a stop 22 secured to one of the uprights 12.

When it is desired to bring the board from its closed position, as seen in Fig. 2, to its open position, as seen in Fig. 3, it is momentarily tilted laterally to rest on one trunnion so that the board may clear the stop 22, and it is then swung forwardly about its trunnions 19 which pivot on the upper edges of the legs 21 of the L-shaped guides 20. The trunnions are then moved upwardly against the guides 20 simultaneously with a further forward and downward movement of the outer end of the board. A transverse support 23 extends between the uprights 12 at the upper ends of the guides 20, and when the trunnions reach the upper edge of the support they are slid inwardly and downwardly along the inclined upper face 24 of the support, the board being held in an inclined position during this movement. The outer end of the board is then lowered to rock the inner end on the forward upper edge 25 of the transverse support 23 until the trunnions rest in concave pockets 26 in the lower edge of a transverse support 27 extending between the uprights 12 and against the rear panel 11. This last movement of the board brings it into a horizontal position with the trunnioned end held against vertical displacement by its engagement with the forward upper edge 25 of the transverse support 23 and the lower face 28 of the transverse support 27, while the concave pockets in the transverse support 27 in which the trunnions 19 rest will prevent the horizontal displacement of the board. The board-receiving entrance passage between the transverse supports 23 and 27 may be defined as inclined rearwardly and downwardly, constraining the movement of the board therethrough in correspondingly inclined position, and it will be apparent that the placement of the upper forward edge 25 of the lower support with respect to the lower edge of the upper support is the essential consideration in determining such movement of the board.

The concave pockets 26 in the transverse support 27 are preferably formed by shaping a wooden member with a cross section identical with that through the concave recess desired and then cutting the underside away at the intermediate and end portions to form the lower flat face 28, thus leaving projections 27' near its ends containing the recesses and forming depending abutments 10 at the forward edges of the concave recesses.

In securing the ends of the transverse supports 23 and 27 in the uprights 12, they are preferably let into recesses 29 in the inner faces of the uprights, and are secured there- 15 in by nails 30 or other fastening members.

To support the board 16 in its horizontal position, arms 31 are pivoted by dowels 32 to the ends of a cleat 33 secured transversely below the board intermediate its ends. The 20 arms 31 are held in spaced relation by cross pieces 34 to form a rigid frame 35 and are inclinable to bring their lower ends into abutment with a cross piece 36 secured between the uprights 12 of the housing frame, 25 preferably adjacent one of the cross members 13. In order to relieve the dowels 32 of thrust the upper ends 37 of the arms 31 are suitably rounded to bear in concave sockets 38 formed adjacent the ends of the cleat 33, 30 as seen in Figs. 1 and 3.

The lower ends of the arms 31 are guided into abutment with the cross piece 36 by a metal rod 39 passing through slots 40 in the arms and secured between the uprights 12 35 of the housing frame. The rod 39 also facilitates the folding of the board and prevents the outward movement of the lower end of the board when it is in folded condition.

The board 16 is brought to its closed position by lifting the free end to the inclination shown in dotted lines in Fig. 4, whereupon it is withdrawn to bring the trunnions 19 forwardly of the transverse support 23, from which position the trunnions descend to a 40 position adjacent the upper edges of the legs 21 of the guide members 20 simultaneously with an upward swinging movement of the board to its vertical position against the transverse support 23 and behind the stop 22, 45 which it passes by being tilted laterally when engaging the outer cam surface 22' of the stop.

A sleeve board 31 has one end provided with trunnions 42 similar to those on the 50 board 16. The trunnions are journaled in recesses 43 in the uprights 12 at a suitable height above the transverse support 27 and adjacent the rear panel 11. In its closed position, as seen in Fig. 2, the sleeve board 55 is held in a vertical position by its engagement with a spring clip 44 secured to the panel 11. In the open position ready for use, as seen in Fig. 3, the sleeve board is secured in a horizontal position above the 60 board 16 by a brace member 45 pivoted to a

bracket 46 secured to the underside of the board, the lower end of the brace member being in abutment with the transverse support 27 and the panel 11. The board 16 holds the garments off the floor in a convenient location adjacent the sleeve board when the latter is in operative position. When not in use during the course of an ironing, the sleeve board may be readily 70 swung back out of the way to a vertical 75 position.

The two lower cross members 13 and the uprights 12 form a compartment 47 in which the iron and other equipment may be stored 80 when not in use.

The device of the present invention is of simple and compact character and the boards lock rigidly in operative position with very little manipulation. The construction of the device affords facility in 85 assembly and enables it to be inexpensively manufactured.

What I claim as new and desire to secure by Letters Patent is:

1. In an ironing cabinet, the combination 90 of a frame including spaced uprights, a pair of transverse members extending horizontally between said uprights and spaced to form a board-receiving entrance passage between them, one of said transverse members being disposed above the other and having a pocket in its lower face defined at its forward edge by a depending abutment spaced rearwardly from the upper edge of said lower transverse member, and an ironing board having its inner end movable between said uprights and provided with a projection adapted to seat in said pocket behind said abutment, the inner end of said ironing board being slidably engageable 100 with the upper edge of said lower transverse member during insertion into said passage and being adapted to fulcrum on the upper edge of said lower transverse member after such insertion for effecting a horizontal disposition of the board and for seating said projection in said pocket in engagement with said depending abutment to prevent the forward displacement of the board, and said board being alternatively retained in upright position within the frame in front of the lower transverse member and with the inner end of said board below said transverse members.

2. In an ironing cabinet, the combination 120 of a frame including spaced uprights, a pair of transverse members extending horizontally between said uprights and spaced to form a board-receiving entrance passage between them, one of said transverse members being disposed above the other end having pockets in its lower face adjacent its ends, each pocket being defined at its forward edge by a depending abutment spaced rearwardly from the upper edge of said 125

lower transverse member, and an ironing board having its inner end provided with trunnions movable between said uprights and adapted to seat in said pockets, the inner trunnioned end of said ironing board being slidably engageable with the upper edge of said lower transverse member during insertion into said passage and being adapted to fulcrum on the upper edge of 10 said lower transverse member after such insertion for effecting a horizontal disposition of the board and for seating said trunnions in said pockets in engagement with said depending abutments to prevent the forward 15 displacement of the board, and said board being alternatively retained in upright position within the frame in front of said lower transverse member and with the inner end of said board below said transverse members.

20 3. In an ironing board cabinet, the combination of a frame including spaced uprights, an ironing board movable at one end between said uprights and provided with trunnions at said end, a transverse support 25 extending between said uprights at an inter-

mediate portion and having an inclined upper face terminating at an elevated forward edge, a second transverse support spaced upwardly and rearwardly from said first-named transverse support and including depending abutments at its ends defining the forward edges of trunnion-receiving pockets and defining with said lower support an inclined entrance passage for said ironing board, said ironing board being longitudinally movable into said inclined passage between said supports in a rearwardly and downwardly inclined position and movable to a horizontal position after entry between said supports by rocking it on said lower support to bring said trunnions upwardly into said pockets, and means for retaining said board in an upright position within the frame in front of said supports and with the inner end of said board below said supports.

In testimony whereof, I affix my signature.

DAY CHANNING McCRAY.
